UNITED STATES PATENT OFFICE.

EDMUND W. DEHLER AND MARY DEHLER, OF SYRACUSE, NEW YORK.

CAR TRUCK.

Application filed February 5, 1924. Serial No. 690,742.

To all whom it may concern:

Be it known that we, EDMUND W. DEHLER and MARY DEHLER, citizens of the United States of America, of Syracuse, in the county of Onondaga in the State of New York, have invented new and useful Improvements in Car Trucks, of which the following, taken in connection with the accompanying drawings, is a full, clear, and

exact description.

This invention relates to a railway car truck involving the use of a symmetrical frame and a pair of parallel axles journaled therein and each provided with a pair of flanged wheels adapted to roll along the track.

The side plates or sills and cross bars commonly employed in trucks of this character are frequently made of cast iron or specially molded designs requiring re-enforcing ribs and flanges formed integral therewith, all of which adds greatly to the weight and cost of the truck without removing the inherent liability of breakage especially in freezing climates.

The main object of the present invention is to produce a comparatively light, strong and durable truck by constructing the major portions of the frame from boiler iron or sheet steel commonly carried in stock and capable of being stamped or cut to the desired form and size in a single punching operation which enables the parts to be easily and quickly assembled without special machine work and thereby greatly reduces the cost of manufacture and at the same time, increasing the production or output for a given period of time.

Another object is to make the side plates or sills of uniform size and shape so that they may be stamped by the same dies and may be used at either side of the truck or reversed end for end.

Another object is to connect the ends of the side plates or sills by suitable fenders or bumpers of boiler iron or sheet steel and to make said fenders of the same form and size so that they may also be interchanged or reversed end for end when applying them to the side plates.

A further object is to reduce the weight of the side plates or sills by cutting away the central portions thereof and leaving integral connecting portions above and below the openings for bracing purposes.

Another object is to re-enforce the upper

central portions of the side plates with separate angle irons which may be cut to the desired lengths from stock material and put in place.

Other objects and uses relating to the manner of re-enforcing the journal bearing guides for the axles and for bracing the plates across said guides will be brought out in the following description.

In the drawings:—

Figure 1 is a perspective view of a railway car truck embodying the various features of our invention.

Figure 2 is a transverse vertical sectional view taken on line 2—2, Figure 1.

Figure 3 is a perspective view of one of the detached side plates and its re-enforcing angle iron removed therefrom.

Figure 4 is a perspective view of the parts of one of the guides for one of the journal boxes.

Figure 5 is a perspective view of one of the journal boxes.

Figure 6 is a perspective view of one of the yokes for bridging the underside of the openings for one of the guide openings in the side plate or sill, and Figure 7 is a perspective view of the opposite halves of one of the journal bearings adapted to be placed in one of the journal boxes for receiving the adjacent end of one of the axles.

As illustrated, this truck comprises a pair of similar lengthwise side plates —1— arranged edgewise vertically in transversely spaced relation parallel with each other, said plates being preferably made of boiler iron or equivalent flat sheet metal and having their central portions of greater vertical depth than their ends and provided with parallel lower and upper edges.

The intermediate portions of these plates are provided with longitudinally elongated openings —2— between their lower and upper edges forming lengthwise base bars —3— at the lower sides of said openings, but of less vertical height than the portions of the plates above the openings thereby reducing the weight of the plates and at the same time maintaining sufficient strength to resist the strains to which the plates are subjected.

The portions of each plate —1— at opposite ends of the opening —2— are provided with vertical slots or openings —4— extending upwardly from the lower edge thereof and at right angles thereto for re-

ceiving separate pairs of upright guide plates —5—, top plates —6— and journal boxes —7— hereinafter more fully described.

- 5 The opposite ends of the side plates are substantially identical in that they extend the same distance beyond the openings —4— and are preferably tapered edgewise vertically to the same form and size to form convenient means for attaching opposite end fenders or bumpers —8— thereto.

The side plates —1— are re-enforced by angle irons —9— having their upright flanges rigidly secured by rivets —10— or equivalent fastening means to the inner faces of the upper portions of the plates so that their horizontal flanges will lie in substantially the same horizontal plane as the upper straight edges of the intermediate portions of the plates, said angle irons being extended longitudinally across and above the openings —4— and in substantially the same vertical planes as the outer end walls of said openings for re-enforcing the reduced stock above the openings —3— and —4— and also affording means for supporting brakes and other mechanism which it may be necessary to mount upon the truck.

Aside from the flanges —9— and other attachments, the plates —1— are substantially flat from end to end and the intermediate portions of their lower and upper edges form points just outside of the openings —4— and are straight and parallel except where the openings —4— are formed.

The fenders or bumpers —8— are identical and interchangeable and may be made of boiler iron or sheet steel and are preferably U-shaped in plan to form opposite arms —8'—, the ends of which are spaced apart a distance corresponding to the distances between the outer faces of the opposite plates —1— so as to overlap upon said faces and permit them to be secured thereto by bolts —10—.

The portions of the arms —8'— adjacent the end edges of the plates —1— are contracted or drawn toward each other to form shoulders —11— adapted to abut against said end faces and thereby to not only brace the ends of the plate —1—, but also to relieve the bolts from shearing strains by transmitting inward end thrust directly to the side plates.

55 The vertical width of each fender —8— is substantially equal to that of the adjacent ends of the plates —1— and therefore, the fenders are deposited, in horizontal planes between the lower and upper edges of the intermediate portions.

Each of the openings —4— is equipped with a set of guide plates —5— and top plates —6— which are comparatively small and may be made of metal forgings or of case metal.

The guide plates —5— are inserted from the outside inwardly into the corresponding opening —4— and extend from top to bottom thereof, said plates being provided with oppositely projecting branches —12— adapted to engage the outer face of the side plate —1— at opposite sides of the opening —4— and to be secured thereto by bolts or rivets —13—.

The inner faces of these guide plates —5— are substantially flat and extend transversely beyond their respective ribs —12—, the portions at the inner sides of the flanges being of greater transverse width than the corresponding thickness of the plate —1— so as to project some distance beyond said plate.

When these guide plates are secured in operative position, their upper edges abut against the top wall of the opening —4—, the flanges —12— being extended downwardly from the upper edges of the plates and terminated some distance above the lower edges thereof to permit the placing of a U-shaped yoke or bridge piece —14—, Figure 6, in operative position as will be presently described.

The top plate —6— of each guide set is inserted from the outside inwardly through the opening —4— and against the upper wall thereof so as to rest between the upper ends of the guide plates —5— and hold said plates in spaced relation, said top plate —6— being provided with an upstanding flange —6'— adapted to be bolted or otherwise secured to the outer face of the sill plate —1— in the vertical plane of the flanges —12—, the flange —6'— being extended beyond its main body —6— so as to rest upon the upper ends of the plates —5— when adjusted for use.

Each of the journal boxes —7— is adapted to slide vertically in one of the guides formed by the guide plates —5— and —6— and is preferably placed in operative position through the lower open side of the guide before the yoke —14— is placed in operative position and in order that it may be held against endwise displacement is provided with opposite end flanges —7'— in spaced relation corresponding to the transverse width of the plates —5— so as to slidably engage the inner and outer upright edges of said guide plates, it being understood that the opposite sides of each journal box between the flanges —7'— are substantially flat and parallel and are adapted to slidably engage the inner faces of the guide plates —5—.

Each journal block —7— is also provided with a central core opening —15— extending therethrough from end to end for receiving the lower and upper journal bearing sections —16— and —16'— which are of less length than the journal box —7— and placed in operative position through the inner end of the

opening —15—, the outer end of said opening being reduced in size to form a stop shoulder —17— for limiting the outward movement of the journal sections —16— and 5 —16'—.

As previously stated, the truck frame is adapted to receive a pair of parallel axles —18— each having a pair of flanged wheels —19—, the outer ends of each axle being reduced in diameter and journaled in the adjacent bearings —16— and —16'— and forming shoulders —19— which are engaged with the inner ends of said bearings to hold the latter against inward displacement and 15 against the shoulders —17—.

The outer ends of the openings —15— in the journal boxes —17— are normally closed by cover plates —20— which are pivoted at —21— to the upper portions of the boxes to 20 permit them to swing in vertical planes to and from their closed positions so that when closed they form oil pockets —22— for lubricating the journal bearings for the axles.

25 Suitable coil springs —23— are interposed between the upper faces of the journal boxes —7— and lower faces of the top plates —6— to yieldingly support the frame bars —1— and body of the car mounted thereon.

30 The axles —18— with the wheels and journal boxes thereon may be placed in operative position in the openings —4— of the frame bars —1— through the open lower ends thereof after which the yokes —14— 35 may be secured in place to hold the journal boxes —7— and frame bars against relative vertical displacement, and for this purpose each yoke is U-shaped in side elevation and has its opposite arms bifurcated or slotted 40 at —24— to receive the lower edges of the frame bars —1— at opposite ends of its opening —4—, said arms and adjacent portions of the plate —1— being provided with registering bolt openings for receiving bolts 45 —25— by which the yokes are firmly secured in place with the bottoms of the slots —24— seated snugly against the lower edges of the side plates —1— and the journal boxes —7— 50 yieldingly held against the underlying portions of the yokes by the springs —23—.

The operation of our invention will be understood upon reference to the foregoing description and the accompanying drawing.

and it is evident that a structure of this character is particularly light, strong and durable and may be manufactured at a comparatively low cost and at the same time is free from any of the objectionable ribs and re-enforcing projections commonly employed in cast metal truck frames. 60

We claim:

1. In a railway car truck, a frame comprising a pair of flat sheet metal side plates arranged edgewise vertically and each of uniform thickness throughout its area and provided with a pair of transverse openings extending upwardly from its lower edge at equal distances from its ends, in combination with journal boxes movable in said openings, and yokes extending across the undersides of the journal boxes and provided with slotted arms engaging the inner and outer faces of the plate at opposite ends of their respective openings. 70

2. A railway car truck as in claim 1, in which the side plates are provided with similar transverse openings between the first openings and intermediate the lower and upper edges of said plates, the plates being continuous across the lower and upper sides 80 of the second named openings. 75

3. A railway car truck as in claim 1, in which angle irons are secured to the inner faces of the side plates above the transverse openings. 85

4. In a railway car truck, a frame comprising a pair of flat sheet metal side plates arranged edgewise vertically and each of uniform thickness throughout its area and provided with a pair of transverse openings extending upwardly from its lower edge at equal distances from its ends for receiving journal boxes for the axles, and angle irons secured to the inner faces of the side plates with their upper sides substantially coincident with the upper edges of said plates and their opposite ends extended over the transverse openings. 90 95

In witness whereof we have hereunto set our hands this 2nd day of February, 1924.

EDMUND W. DEHLER.
